GAME BOARD

Frank L. Lindstrom, Bridgeport, Conn.

Application December 30, 1933, Serial No. 704,681

6 Claims. (Cl. 273—121)

This invention relates to new and useful improvements in game apparatus.

An object of the invention is to provide a game board including improved structural features 5 whereby the same is strong and durable and yet may be manufactured at low cost.

A further object is to provide a game board including an improved arrangement of obstructions or barriers whereby the movements of 10 game pieces about or over the face of the board are guided and controlled.

An additional object is to provide improved means for securing barriers or guides in place on a game board.

15 A further object is to provide a game board including an opening and a prop to extend partially into the opening to support the board at an incline and provide a cup to receive a playing piece.

20 Other objects and advantages will become apparent from a consideration of the following detailed description taken in connection with the accompanying drawing wherein a satisfactory embodiment of the invention is shown. However, 25 it will be understood that the invention is not limited to the details disclosed but includes all such variations and modifications as fall within the spirit of the invention and the scope of the appended claims.

30 In the drawing:

Fig. 1 is a top plan view of the improved game board;

Fig. 2 is a transverse sectional view taken substantially along the line 2—2 of Fig. 1;

35 Fig. 3 is a detail sectional view taken substantially along the line 3—3 of Fig. 1;

Fig. 4 is a detail sectional view taken substantially along the line 4—4 of Fig. 1; and

40 Fig. 5 is a detail sectional view taken substantially along the line 5—5 of Fig. 1.

Referring in detail to the drawing, the improved apparatus includes a base member or board 10, the lower edge of which may be square 45 and the upper edge of which may be rounded as shown. The board is substantially rectangular with the exception of its upper curved edge. A sheet metal strip 11 is disposed about the sides and upper or curved edge of the board and is secured to such edges by tacks or the like 12 and projects about the upper or playing surface of the board as clearly shown in Figs. 2 and 3.

50 On the playing surface of the board or base 10 and at one side edge thereof there is arranged a projecting device generally designated 13 and

comprising a housing including a sheet metal angle member 14 arranged with its arm 15 in spaced and substantially parallel relation to a side portion of the strip 11 and having the free edge 16 of said arm out-turned and secured to the base as by tacks or nails 17. The arm 18 of said member 14 forms the upper or roof member of the housing of the projector and has its free edge 19 down-turned and embracing the outer surface of the upper edge portion of the strip 11 as 10 shown in Fig. 2. In the said arm 18 an opening 20 is provided for the introduction of marbles or other playing pieces into the projector.

The actual projecting part or means of the projector 13 comprises a rod or plunger 21 the 15 inner end of which carries a washer-like member 22 between which and a stop 23 there is located a coil spring 24 the latter being disposed about the rod. The outer end of the rod passes through the stop 23 and a wall 25 closing the outer end 20 of the housing of the projector and is secured to any suitable hand or finger piece 26 which by engagement with the wall 25 limits movement of rod or plunger 21 under the influence of spring 24. Obviously, on a marble being introduced into 25 the projector through the opening 20 the marble will be in advance of the shooter or gun comprising the actual projecting means and on the hand piece 26 being drawn outwardly the rod 21 will be drawn outwardly in a direction to compress 30 the spring 24 and as the marble will move inwardly of the projector as the inner end of the rod 21 moves inwardly the said marble will be shot through the projector by expansion of the spring on release of the hand piece 26.

35 A member 27 closes the playing field between the end 28 of the strip 11 and the member 14 of the projector at the lower end of the base 10. This member 27 is a channel member or is transversely substantially in the form of an inverted 40 U and is made up of sheet metal. The free edge portion of the arm 29 of the member is tacked to the lower edge of the base 10 as at 30 and the connecting portion 31 of said member is disposed over the lower edge portion of the base 10 and the other arm 32 of said member at its free edge abuts the upper or playing surface of the base 10. Relatively long nails 33 may be passed 45 through the connecting portion of the member and into the base as best shown in Fig. 5. At one end the connecting portion 31 of member 27 carries a lip or flange 34 which is downturned over the upper edge of the end portion 28 of strip 11 whereby said strip is further supported. 50

A pair of guide or barrier members 35 and 36 each formed of a length of strip sheet metal stock are arranged each with one edge against the upper or playing surface of the base 10 and 5 so project perpendicular to said surface. Member 36 includes a portion 37 curving inwardly toward the longitudinal center line of the base and a portion 38 curved in the opposite direction and continuing on to provide a curved portion 39 extending across the extreme lower end of the 10 playing field. Guide or barrier 35 includes an upper curved portion 40 arranged in spaced relation to the upper curved edge of the board and continuing on into a curved portion 41 corresponding with the curved portion 37 of member 36 and a curved portion 42 corresponding with the curved portion 38 of member 36.

A pair of similar sheet metal members 43 are associated one with each of the guides or barriers 35 and 36 and said members 43 are each transversely substantially in the form of an inverted L and each includes an outer straight wall portion 44 the free and lower edge of which is disposed against the upper surface of the base 10 and each of said members also includes an upper arm 45 which arm has its free edge portion shaped to correspond with the curved portions 37 and 38 and 40 and 41 of the members 36 and 35 respectively. This is best shown in 20 Fig. 1 and from Fig. 2 it will be noted that adjacent their free edges the arms 45 of the members are pressed to provide grooves 46 which grooves receive the upper edge portions of the portions 37 and 38 and 41 and 42 of the members 36 and 35 respectively. Suitable means, as, for 25 example, relatively long nails 47, may be passed through the arms 45 of the members 43 whereby to secure such members to the base 10.

The end portion 48 of the member 36 is in engagement with the strip 11 and, if desired, a few pins 49 may be associated with the opposite end of said member and a few pins 50 may be associated at the upper end of the member 35. Pins 49 and 50 form extensions of the members with 30 which they are associated. The path of travel of a marble shot from the projector 13 is along a path at the inner side of the strip 11 from the discharge end of the projector to the point where the end 48 of member 36 engages the strip and 35 then the marble follows such member 36 to the juncture of its portions 37 and 38 from whence the marble moves across the board to follow around at the inner side of the curved portions 40 41 and 40 of the member 35.

Of course, the distance the marble travels will 45 depend on the force with which the marble is projected and the marble may travel beyond the free end portion of member 35 and engage the pins 50 or it may pass through the space 51 between the pins 49 and 50 or it may pass downwardly between the portion 37 of member 36 and the portions 40 and 41 of member 35 or it may engage the said portion 37 and on leaving the same 50 cross the board to engage the portion 42 of member 35. From this last it will be seen that the marble may take a course substantially in the shape of a figure eight (8).

Any suitable design as, for example, the stars and the like shown in Fig. 1, may be formed on 55 the playing surface of the board, and suitable pockets 52 are provided at spaced points over the playing surface of the board for the reception of the shot marbles. It will be appreciated that the different pockets may be marked to in-

dicate different numbers or points scored by a player depending on which pocket a marble shot by him moves into.

When a board is in use it is supported in an inclined position and to this end base 10 is provided with an opening 53 into which the upper end of a peg or prop 54 enters. This peg or prop extends only partially through the opening 53 whereby the upper portion of said opening constitutes a receptacle in which a marble may seat. The prop will support the upper end of the game board in position above a table or the like so that the board will be held at an incline and a projected marble when its force is spent will tend to gravitate toward the lower edge of the board and may enter one or the other of the pockets or not as the case may be.

It will be understood that the prop 54 is removable from the opening 53 so that said prop may be disposed on the playing surface of the board when the game is not being used whereby the entire device may be slipped into a flat box or the like. Pins or other obstructions 55 may be arranged at any desired points over the surface of the board so as to be engaged by moving marbles and change the direction of the marbles. A row 56 of pins is provided toward the lower end of the base 10 but inwardly of the portion 39 of the guide or barrier 36 and such row of pins extends for a substantial distance to 30 each side of the longitudinal center of the base and acts to catch marbles which have passed downwardly of the board without entering any of the pockets 52. Obviously, the barrier or row of pins or other means 56 will to a large extent 35 serve to prevent the marbles which do not score from passing into the lower portion, designated 57, of the raceway and interfering with or slowing up succeeding marbles being shot through the raceway.

The guides or barriers 35 and 36 being formed of strip stock are made without any waste of material such as would likely result if they were blanked out. It is but necessary to cut off lengths of the strip stock and owing to the manner in 45 which the strips are supported or attached to the base 10 they may be of light gauge. At desired intervals along their lengths the strips are engaged by clips 58 which clips are formed of short lengths of fairly wide flat stock and each includes 50 an in-turned or hooked upper end portion 59 receiving an upper edge portion of one of the strips 35 and 36 and each having its lower end portion out-turned as at 60 and through which is passed a brad or other securing means 61.

These clips serve to draw the lower edges of the guides or barriers 35 and 36 firmly against the playing surface of the base and these clips being relatively wide engage the said barriers or guides over a substantial area and hold them firmly against wobbling or against assuming positions other than positions substantially perpendicular with respect to the playing surface of the base. The hooked upper ends of the clips quite snugly receive the upper edge portions of the strips forming the barriers and additionally they prevent any upward or outward movement of the guides or barriers relative to the base.

In constructing the improved game board the 70 base 10 may be of wood so that the various fastening means securing the strip 11 and member 27 and clips 58 to the base may be driven in. All of these sheet metal parts are preferably plated to give a neat and finished appearance. 75

Since the apparatus includes essentially only a board of wood, sheet metal strips, and nails or pins it will be clear that the apparatus may be constructed with a minimum of expense, there being no waste of metal, the various strips being of the proper width and cut to length. Also, the member 27 at the lower edge of the base being of considerable width adds greatly to the appearance of the apparatus and gives a good wide surface on which to rest the hand to steady the device.

A sheet or label having any desired design thereon may be glued or pasted to the upper surface of the base to provide a playing field. In the drawing designs are shown on the upper and lower portions of the playing field and the design in each instance includes a star superposed on a series of concentric strips forming a bull's eye. The cups or pockets at the centers of the stars are shown as including portions in the form of metal strips and said portions, designated 62 may be secured in place by clips similar to clips 58 or they may be provided on their lower edges with prongs or teeth to be pressed into the base. It should also be noted that the barrier 56 serves to prevent a marble or other game piece which does not score from gravitating downwardly into the portion 57 of the raceway. Of course, it will be understood that the pins providing the cups 52, obstructions 55 and barrier 56 are held in place simply by being partially driven into the base.

Having thus set forth the nature of my invention, what I claim is:

1. In a game board, a base providing a field, a sheet metal strip about and secured to the edge of said base and extending above the upper surface thereof, means for projecting a game piece across the face of said base, a pair of shaped sheet metal strips each having an edge against the playing surface of the base and forming game piece guides or barriers, said shaped strips arranged in spaced relation and having portions at opposite sides of the center of the base curved inwardly and then outwardly toward and from the center of the base, a sheet metal piece associated with each of said shaped strips, said pieces substantially inverted L-shaped in transverse section and each having the edge of one arm against the playing surface of the base at the outer side of its shaped strip and having the edge of its other arm shaped as the mentioned portion of its strip and engaging the upper edge thereof, means engaging the said other arm of each of said pieces and securing them to the base, and means forming pockets about the surface of the base between said shaped strips.

2. In a game board, a base providing a playing field, an upstanding flange about the edge of said field, means for projecting a marble onto said field, means for guiding the marble about the field, means forming pockets at spaced points about the field to receive marbles, said base having a hole therethrough adjacent its upper edge, a peg entering said hole from the lower side of the base and removable therefrom and serving to support the base in an inclined position, and said peg extending only partially through the base whereby the upper portion of said hole may receive a marble projected onto said field.

3. In a game board, a base providing a playing field and having side, upper and lower edges, a sheet metal strip about the side and upper edges of said base and secured to said edges and extending above the playing field, a sheet metal member at the lower edge of said base, said member substantially in the form of an inverted U and having the free edge portion of one arm secured to the lower edge of the base, said member having its connecting portion extending over the base and having the free edge of its other arm engaging the playing surface of the base, an extension on one end of the connecting portion of the member and over-lapping the upper edge of an end portion of said sheet metal strip, means to project a marble across the face of the base, and means forming pockets at spaced points about the face of the base.

4. In a game board, a base providing a field, a sheet metal strip about and secured to the edge of said base and extending above the upper surface thereof, means for projecting a game piece across the face of said base, said means including a housing and a spring pressed means in the housing, said housing comprising a sheet metal angle member having the free edge of one of its arms bent and hooked over the upper edge of said strip, and said member having the free edge of its other arm out-turned and secured to said base.

5. In a game board, a base providing a field, a strip about and secured to the base and extending above the upper surface thereof, means for projecting a game piece across the face of said base, a shaped sheet metal strip having an edge against the upper surface of the base and having the lower portion of its inner surface forming a game piece guide or barrier inwardly of the edges of the base, means securing said strip to the base, said means including a clip at the outer side of the strip and having a hook at its upper edge snugly receiving the upper edge of the strip, said clip including relatively broad flat surfaces engaging the upper portion of the inner surface of the strip and the outer surface thereof for the height thereof, said clip having its lower end portion out-turned in a direction away from the strip to provide a foot piece against said base, means securing said foot piece to the base, and means forming pockets about the playing surface of the base.

6. In a game board, a wood base providing a field, a sheet metal strip about the edge of said base and extending above the upper surface thereof, means passing through the strip and into the base and securing the base and strip together, means for projecting a game piece across the face of said base, a pair of shaped sheet metal strips each having an edge against the playing surface of the base and forming game piece guides or barriers, means passing into the base and securing the shaped strips thereto, said shaped strips arranged in spaced relation and having portions at opposite sides of the center of the base curved inwardly and outwardly toward and from the center line of the base, means securing said strips to the base, and means forming pockets about the surface of the base between said shaped strips.

FRANK L. LINDSTROM.
